UNITED STATES PATENT OFFICE.

JULIAN KENNEDY, OF PITTSBURGH, PENNSYLVANIA.

WEAR PLATE FOR FURNACES.

Application filed December 3, 1924. Serial No. 753,617.

The present invention relates broadly to furnace structures, and more particularly to a blast furnace structure and an improved form of wear plate and supporting means 5 therefor, although the utility of the invention is not limited in this respect.

It is desirable in the art to which the present invention relates to provide a wear plate so constructed that it may be readily removed 10 as may be desirable by reason of wear or breakage. It is further desirable to support such wear plate so that it will not interfere with the normal operation of charging the furnace and, at the same time, will tend to 15 hug the furnace wall in such manner as to effectively protect the same.

It is the object of the present invention to provide an improved wear plate possessing 20 the advantageous features of construction referred to, together with other advantages that will be readily apparent as the invention becomes better understood by reason of the following specification and accompanying drawings forming a part thereof.

25 In the drawings there is shown, for purposes of illustration only, a preferred embodiment of the present invention, it being understood that the drawings do not define the limits of my invention as changes in the 30 construction and operation disclosed therein may be made without departing either from the spirit of the invention or scope of my broader claims.

In the drawings:—

35 Figure 1 is a top plan view of a portion of a furnace provided with wear plates constructed in accordance with the present invention;

40 Figure 2 is a side elevation of the construction illustrated in Figure 1;

Figure 3 is a perspective view of one of the rail plate sections;

45 Figure 4 is a vertical sectional view, partly broken away, and on an enlarged scale, through the wear plate illustrated in Figure 3.

Figure 5 is a top plan view, partly in section, of my improved wear plate;

50 Figure 6 is a front elevation of the wear plate;

Figure 7 is a rear elevation of one of the supporting brackets;

Figure 8 is a vertical sectional view on the line VIII—VIII of Figure 7, and

Figure 9 is a top plan view of the bracket 55 shown in Figure 7.

The present invention is adapted for use with furnaces of standard construction which may comprise a wall 2, of brick or other desired refractory material, having a supporting 60 casing 3 usually in the form of metallic shell. Secured to this shell at spaced points thereon and projecting inwardly therefrom are brackets 4 comprising vertically extending back plates 5, horizontally extending supports 6 and reinforcing webs or flanges 7. The back plates may be provided with a series 65 of openings 8, by means of which the brackets may be secured in position, and the horizontally extending supports 6 are preferably 70 formed with a vertically extending shoulder or hook 9 and a reinforcing and dividing rib 10.

Adapted to be supported between adjacent 75 brackets 4 are wear plate sections 11 comprising skirts or body portions 12 and off-set supporting extensions 13. These supporting extensions are preferably each formed with downwardly projecting shoulders or hooks 15 of slightly less width than the width of the 80 extensions 13 and dimensioned to fit between the ribs 10 on adjacent brackets and overhang the shoulders 9 formed thereon.

The extensions 13 are of such nature that 85 they provide a support located at one side of the center of gravity of the wear plate sections whereby, when the sections are in position on the brackets 4, they will tend to swing outwardly into contact with the inner surface of the furnace wall 2. By reason of this construction, the sections tend automatically to 90 assume the desired position when disturbed or replaced for any reason whatsoever.

Formed on each of the wear plate sections, and preferably on the extensions 13, is a 95 lug 16 having an opening 17 therein. These openings 17 are preferably so arranged that they lie on the opposite side of the center of gravity of the sections from that occupied by the shoulders 15. By reason of this con- 100

struction, when the openings are engaged by any desired lifting means, for the purpose of effecting their removal, the sections tend to swing inwardly toward the center of the furnace. This enables the sections to be more readily removed without interference with the remaining sections. It is desirable, however, that these sections, when in position, form a substantially continuous wear plate. 10 If such a construction is provided, a substantially complete covering for the upper portion of the furnace wall is provided and, at the same time, the sections are close enough to prevent undue movement thereof. From 15 the standpoint of a relatively close engagement between the sections, it would be desirable to so shape the sides of the skirts or body portions 12 that the division plane therebetween would substantially coincide with 20 radial lines extending outwardly from the center of the furnace. If such a construction were employed, however, it would be comparatively difficult to effect the independent removal or insertion of an individual 25 section. In order to obtain the advantages of a construction of the character described, while permitting easy renewal of the sections, the sides of the sections throughout the major part of the upper portion thereof, 30 as indicated at A, extend in substantially parallel planes, while the remainder of the sides, as indicated at B, extends in planes converging toward the center of the furnace and substantially coinciding with radial 35 lines drawn from the center of the furnace.

With the construction as above described, the sections will be substantially interlocked at their lower ends, while permitting the sections to be relatively easily disengaged by 40 merely raising any desired section relatively to the others a distance equal to the length of the portions B when such section will be free to swing inwardly away from the other sections, as determined by the location of the 45 openings 17. During insertion of a section, the reverse operation will take place, the sections interlocking as they approach their final resting positions on the brackets 4.

The ribs 10 on the brackets 4 tend to center the sections as they are lowered into position and thereafter to prevent movement of the upper portions thereof, while the extensions 13 on the wear plate sections extend over the supporting shoulders 9 on the 55 supports 6 in such manner as to effectively protect the same. It will be understood that if desired, the wear plate sections may be reinforced by the use of webs or flanges 18 between the skirts 12 and the extensions 13.

With the wear plate sections inserted in the upper end of the furnace, they retain positions adjacent the furnace wall whereby they occupy a minimum amount of room. At the same time, they provide a substantially 60 continuous protecting surface of such char-

acter that the usual bell utilized with such furnace may be lowered into position thereon.

The advantages of the present invention arise from the provision of a wear plate constructed of a plurality of sections adapted to be individually removed or replaced. 70

Further advantages arise from the construction of the supporting brackets and the location of the supports whereby the sections, 75 when in position, tend to swing outwardly against the furnace wall.

I claim:

1. A wear plate comprising a plurality of 80 separately removable sections, means for supporting said sections to permit removal thereof and means associated with each of said sections for engaging and positioning an adjacent section, substantially as described.

2. A wear plate comprising a plurality of 85 separately removable sections, means secured to a furnace for supporting said sections to permit removal thereof, and supporting means on each of said sections adapted to be engaged with said first mentioned means 90 while said sections are in position in a furnace, said supporting means being effective at one side of the center of gravity for causing the sections to swing in a predetermined direction when said means are engaged, substantially as described. 95

3. A wear plate comprising a plurality of 100 separately removable sections, brackets secured to a furnace for supporting said sections to permit removal thereof and supporting means on the sections adapted to be engaged with said brackets while said sections are in position in a furnace, said supporting means being effective at one side of the center of gravity for causing the sections to 105 swing outwardly against the inner surface of the furnace wall, substantially as described.

4. As an article of manufacture, a wear plate section for furnaces having a body comprising angularly extending portions with an offset supporting means on one of said portions extending to one side of the center of gravity of the section, substantially as described. 110

5. As an article of manufacture, a wear 115 plate section for furnaces comprising an arcuate body, a supporting means off-set so as to be effective for supporting the section at one side of the center of gravity thereof, and lifting means on said body effective on the 120 opposite side of the center of gravity, substantially as described.

6. As an article of manufacture, a wear plate section for furnaces having an arcuate body portion with portions of the sides thereof lying in different planes to provide engaging and positioning projections predeterminedly located and supporting means carried thereby, substantially as described. 125

7. As an article of manufacture, a wear 130

plate section for furnaces comprising a body having curved front and rear faces, said body having sides extending in substantially parallel planes throughout a portion of their length and in converging planes throughout another portion of their length, said converging planes providing engaging and positioning projections on the section, substantially as described.

10 8. As an article of manufacture, a wear plate section for furnaces comprising a body having curved front and rear faces, said body having sides extending in substantially parallel planes throughout a portion of their length and in converging planes throughout another portion of their length, said converging planes providing an engaging and positioning projection on the section, and off-set supporting means carried by said section, substantially as described.

9. A wear plate structure for furnaces, comprising a plurality of supporting brackets, each having supports provided with a division rib and an upstanding shoulder, and a plurality of wear plate sections carried by said brackets, said sections having downwardly projecting shoulders engaging the shoulders on said brackets and extending between said ribs, substantially as described.

25 10. A wear plate structure for furnaces, comprising a plurality of supporting brackets, each having supports provided with a division rib and an upstanding shoulder, and a plurality of wear plate sections carried by said brackets, said sections having downwardly projecting shoulders engaging the shoulders on said brackets and extending between said ribs, the shoulders on said sections being off-set whereby said sections when supported on said brackets tend to swing outwardly into a position thereunder, substantially as described.

11. As an article of manufacture, a wear plate section comprising a supporting portion and a body portion, said body portion having a front face of substantially constant width and a rear face having portions of different widths, substantially as described.

12. As an article of manufacture, a wear plate section for furnaces comprising a body, offset supporting means on one side of the center of gravity of said body, and lifting means on the opposite side of the center of gravity of said body, substantially as described.

13. As an article of manufacture, a wear plate section for furnaces comprising a body, offset supporting means on one side of the center of gravity of said body, and lifting means on the opposite side of the center of gravity of said body, said offset supporting means comprising a downturned flange, substantially as described.

14. In combination, a wear plate section, comprising a body portion having support-

ing means, and a bracket adapted to support and center the wear plate section by vertical engagement, substantially as described.

15. In a furnace, a wear plate comprising a plurality of vertically movable sections and means on said sections adjacent the lower ends thereof only for engaging one with another, substantially as described.

16. In a furnace, a wear plate comprising a plurality of vertically movable sections, means adjacent the lower ends of said sections for positioning them with respect to each other, and means for supporting each of said sections at one side of the center of gravity thereof, substantially as described.

17. In a furnace, a wear plate comprising a plurality of vertically movable sections, means adjacent the lower ends of said sections for positioning them with respect to each other, and means for supporting each of said sections at one side of the center of gravity thereof, and lifting means on each of said sections on the opposite side of the center of gravity, substantially as described.

18. As an article of manufacture, a wear plate section, a portion only of each of its lateral faces extending beyond other portions thereof to engage similar portions of adjacent wear plate sections, substantially as described.

19. As an article of manufacture, a wear plate section whose opposite edges have diverging portions and other portions substantially parallel one to the other, substantially as described.

20. As an article of manufacture, a wear plate section whose opposite edges have portions certain parts of which diverge while other portions are at an angle thereto, substantially as described.

21. In combination with a bracket, a wear plate section comprising an arcuate body, and a hook-like means on the body through which its entire weight is supported solely upon vertical engagement with the bracket.

110 22. A wear plate structure for furnaces having a wall comprising a plurality of supporting brackets secured to the furnace in predetermined position in the furnace wall, supporting means on the brackets extending beyond the wall and a plurality of wear plate sections detachably carried by the supporting means.

115 23. A wear plate structure for furnaces, comprising a plurality of supporting brackets secured to the furnace in predetermined position, and a plurality of wear plate sections carried thereby, each section extending between and being supported by adjacent brackets, said brackets and said sections having oppositely directed hooks for vertical engagement one with the other.

120 24. A wear plate section, comprising a body portion having supporting and centering means thereon, and a bracket comprising

means for supporting and centering the wear plate section upon relative movement between the bracket and plate section in a vertical direction, said bracket having an upward standing hook and said wear plate section having a downturned hook.

25. As an article of manufacture, an arcuate wear plate section for furnaces, the

convex surface of the plate section being of greater width throughout a portion of its length than the concave surface, the remaining portion of the convex surface being of less width than the first mentioned portion.

In testimony whereof I have hereunto set my hand.

JULIAN KENNEDY.
